UNITED STATES PATENT OFFICE

MARY E. PHILLIPS, OF LYNN, MASSACHUSETTS.

DESIGN FOR A MEMBER FOR CLAMPS OR FASTENERS.

SPECIFICATION forming part of Design No. 35,234, dated October 29, 1901.

Application filed September 12, 1901. Serial No. 75,238. Term of patent 7 years.

To all whom it may concern:

Be it known that I, MARY E. PHILLIPS, a citizen of the United States, residing at Lynn, in the county of Essex and State of Massachusetts, have invented and produced a new and original Design for a Member of a Clamp or Fastener, of which the following is a specification, reference being had to the accompanying drawings, forming part thereof.

Figure 1 is a plan view of the member, showing my new design. Fig. 2 is an edge view thereof.

As shown in the drawings, the leading or material feature of my design consists of a single strip of metal, the main body portion of which is slightly concavely curved and one end portion of which is bent in a semicircular curve and extends back on itself for a short distance. Said strip is provided with a series of perforations, which are of curved elongated form, they being pointed at one end and rounded at the other and being arranged in pairs side by side symmetrically

with respect to the center line of the member. One or more square perforations are arranged between each pair of elongated perforations. The end of the main body portion is pointed, and two pointed projections are formed on each side of the strip adjacent thereto, the edges of the strip forming these projections being concavely curved. The opposite and upturned portion of the member is provided with an enlarged end, in which a transversely-extending slot is formed.

Having described my invention, what I claim as new, and desire to secure by Letters Patent, is—

The design for a member of a clamp or fastener, as herein shown and described.

In testimony whereof I have signed my name to this specification in the presence of two subscribing witnesses.

MARY E. PHILLIPS.

In presence of—

LOUIS H. HARRIMAN,
G. E. WELDER.
